UNITED STATES PATENT OFFICE.

FRANK F. SIMONS, OF HARMONY, PENNSYLVANIA.

WING-PROPELLER FOR AIRCRAFT.

1,355,112.

Specification of Letters Patent.

Patented Oct. 5, 1920.

Application filed August 21, 1919. Serial No. 319,009.

To all whom it may concern:

Be it known that I, FRANK F. SIMONS, a citizen of the United States of America, residing at Harmony, in the county of Butler 5 and State of Pennsylvania, have invented certain new and useful Improvements in Wing-Propellers for Aircraft, of which the following is a specification.

The primary object of the present invention is the provision of a propeller serviceable for all kinds of aircraft such as aeroplanes, airships and dirigibles whereby a steady straight drive is imparted to the craft during travel through the air, the 15 same being light in weight and simple in construction.

A further object of the invention is the provision of a wing propeller of the reciprocating type that is positively controlled 20 in opening and closing whereby the operation of all the propellers of a set when installed upon an air craft are accurately timed for simultaneous operation.

A still further object of my invention is 25 to positively actuate the members of each wing and giving uniformity to the opening and closing of the propeller during operation.

With these general objects in view the invention consists of the novel combination 30 and arrangement of parts hereinafter more fully described in connection with the accompanying drawings and in which like reference characters designate corresponding parts throughout the several views.

In the drawings,

Figure 1 is a top plan view of my wing propeller closed,

Fig. 2 is a similar view of the propeller 40 open,

Fig. 3 is a transverse sectional view as shown in Fig. 1,

Fig. 4 is a similar sectional view of Fig. 2,

Fig. 5 is a perspective view of an end 45 portion of the propeller open,

Fig. 6 is a perspective view of the opposite end portion thereof,

Fig. 7 is a view similar to Fig. 6, at the opposite side of the propeller,

Fig. 8 is an elevational view of the outer 50 end of the propeller and

Fig. 9 is a perspective view of the trunnioning member adjacent the inner end of the propeller.

55 Referring more in detail to the drawings, my invention is illustrated in the nature of

positive opening and closing means for a propeller of the type found in my pending application upon flying machine, Serial No. 268,147, filed December 24, 1918, whereby 60 the positive opening and closing of the wings 10 and 11 of the propeller is automatically accomplished during the backward and forward movements of the shaft 12, during the swinging operation. 65

A combined trunnioning and stop bracket 13 is fixed to the outer end of the shaft 12, while a trunnioning bracket 14 is secured to the shaft 12 inwardly of the bracket 13, openings 15 and 16 being provided for said 70 shaft through the brackets 13 and 14, respectively. The bracket 13 may be secured to the shaft 12 by struck out portions 17 while the bracket 14 is secured to the shaft by a clevis-form of clamp 18. 75

The wings 10 and 11 have projecting stub axles 19 at the opposite ends of the wings adjacent their inner edges for trunnioning in bearings 20 provided in alinement through the brackets 13 and 14, whereby the 80 wings are permitted to swing toward and away from each other. Strengthening plates 21 are provided at each inner corner of the wings 10 and 11, the said plates at the outer ends of the wings resting upon 85 inwardly projecting stops 22 of the bracket 13 when the wings are outstretched in substantially the same plane, which is calculated to be vertical during the propelling stroke. 90

Inwardly projecting fingers 23 at the opposite side of the bracket 13 from the stops 22 and positioned toward the rear when the propeller is installed upon an aircraft are adapted for engagement by the adjacent 95 plates 21 when the wings 10 and 11 are closed for the recovery stroke. Positive opening and closing means for the wings or blades 10 and 11 are provided for the bracket 14 consisting of a substantially rectangular frame 24 straddling the shaft 12 and slidably mounted through perforations 25 in the parallel sides 26 and 27 of said bracket. These sides 26 and 27 project inwardly toward the fuselage or body of the 100 aircraft, not shown, and the clevis 18, heretofore mentioned, is secured through perforations 28 in the forward side 26 of said bracket with the shaft 12 extending between the sides 26 and 27. 105

Substantially right angular arms 29 have portions 30 at corresponding ends secured

to the wings 10 and 11, and the opposite ends of said arms are pivoted as at 31, to curved links 32, which links are in turn pivoted as at 33, to the forward end of the frame 24. It will be evident that the longitudinal shifting of the frame 24 positively accomplishes the opening and closing of the wings or blades 10 and 11, said arms having intermediate portions 34 suitably curved for 10 accommodating the simultaneous action of the arms. Shoulders 35 are also provided in the arm portions 34 acting as stops for the adjacent wings and assisting the stops 22 in limiting the opening movement of the 15 wings.

Fig. 1 illustrates the propeller in top plan upon its forward recovery stroke with the wings 10 and 11 closed in contact with the fingers 23 of the bracket 13 and an inwardly projecting ledge 27' of the bracket 14. A post or buffer 35 mounted at any convenient point upon the craft 12^b whereon the propeller is installed is located within the circumferential path of movement of the 20 forward pivotal portion 33 of the frame 24, as indicated by the arrow 33'.

When the buffer 35 is struck by said portion 33 of the frame during the forward movement of the propellers, the wings 10 and 11 are forced to their open position with the plates 21 of the wings engaging the stops 22 of the bracket 13 and the shoulders 35 of the arms 29. The propeller is then in position for its rearwardly swinging power stroke with the rear end or cross head 36 of the frame 24 moving in an arcuate line toward the post or buffer 37 suitably positioned upon the aircraft as at 12^b after the manner of the post 35 already described. The engagement of the frame end 36 with the post 37 inscribing the arcuate path indicated by the arrow 36' forcibly closes the blades 10 and 11 with the propeller ready for its forward recovery stroke. 45

The construction and operation of my propellers have been fully set forth and the manner of installation upon an aircraft such as a dirigible or aeroplane will be apparent.

My form of propellers will be provided at 50 opposite sides of the aircraft in pairs or singly as found desirable and by means of the positive opening and closing action herein set forth, the pairs or sets of propellers may be accurately timed for synchronous operation while the individual blades of each propeller will positively operate uniformly.

While the form of the invention herein set forth is believed preferable it will be 60 understood that changes and variations may be made therein without departing from the spirit and scope of my invention.

What I claim as new and desire to secure by Letters Patent is:

65 1. A propeller comprising wings, a swing-

ing shaft, trunnioning brackets for the wings fixed to said shaft, operating arms for the wings, and an actuator slidably carried by one of said brackets pivotally linked to said arms.

70

2. A propeller comprising a swinging shaft, brackets spaced upon said shaft, wings trunnioned adjacent their inner edges between the said brackets and adapted for swinging movement toward and away from each other, and automatic opening means for the wings adapted for operation when the shaft is at the reverse of its swinging movements.

3. A propeller comprising a swinging 80 shaft, brackets spaced upon said shaft, wings trunnioned adjacent their inner edges between the said brackets and adapted for swinging movement toward and away from each other, inwardly projecting stops upon 85 said brackets adapted for flatly engaging the adjacent corner portions of the wings when the wings are outstretched in their operative open position and automatic opening and closing means for the wings carried by one of said brackets.

90

4. A propeller comprising a swinging shaft, brackets spaced upon said shaft, wings trunnioned adjacent their inner edges between the said brackets and adapted for 95 swinging movement toward and away from each other, inwardly projecting stops upon said brackets adapted for flatly engaging the adjacent corner portions of the wings when the wings are outstretched in their 100 operative open position, a frame spanning the shaft slidably carried by the innermost one of said brackets, angular operating arms attached to said wings and pivotal connections between one end of the frame 105 and the adjacent ends of said arms.

100

5. A device of the class described comprising a swinging shaft, brackets fixed to said shaft, wings trunnioned between said brackets, a shiftable frame upon one of said 110 brackets, operating arms for the wings pivotally connected to said frame, and relatively fixed means within the path of travel of the opposite ends of said frame adapted for engagement by the ends of the frame 115 whereby the position of the frame is changed relatively to its mounting bracket during the operation of the device.

110

6. A propeller comprising a swinging shaft, spaced brackets fixed to the shaft, 120 wings trunnioned between said brackets adapted for opening and closing, a frame straddling the shaft and slidably carried by the innermost one of said brackets, simultaneously operating means between said 125 frame and wings, and post members relatively fixed respecting the shaft adapted for engagement by the opposite ends of the frame during the swinging movement of the shaft, whereby the wings are positively 130

opened and closed during the operation of the device.

7. A propeller comprising a swinging shaft, spaced brackets fixed to the shaft, 5 wings trunnioned between said brackets adapted for opening and closing, a frame straddling the shaft and slidably carried by the innermost one of said brackets, simultaneously operating means between said 10 frame and wings, and post members relatively fixed respecting the shaft adapted for engagement by the opposite ends of the frame at the termination of the power and recovery strokes, whereby the wings are automatically opened at the end of the 15 recovery stroke and closed at the termination of the power stroke.

8. A propeller comprising a swinging shaft, wings trunnioned upon the shaft, a 20 frame shiftable perpendicularly of the shaft and operatively connected to the wings, and stop members within the arcuate path of travel of the frame, one of said buffer mem-

bers being adapted for engagement by the adjacent end of the frame when the shaft is 25 at the forward limit of its movement whereby the wings are automatically opened.

9. A propeller comprising a swinging shaft, wings trunnioned upon the shaft, a frame shiftable perpendicularly of the shaft 30 and operatively connected to the wings, and stop members within the arcuate path of travel of the frame, one of said stop members being adapted for engagement by the adjacent end of the frame when the shaft 35 is at the forward limit of its movement whereby the wings are automatically opened, the other stop member being adapted for engagement by the opposite end of the frame when the shaft is at the limit of its 40 rearward swinging movement whereby the wings are automatically closed for the recovery stroke.

In testimony whereof I affix my signature.

FRANK F. SIMONS.
